AQUATIC TORCH OR LIGHT BUOY

Antoine Thiebault, Marseilles, France; vested in
the Alien Property CustodianApplication February 4, 1939, Serial No. 254,521
In France May 9, 1938

3 Claims. (Cl. 102—2)

The present invention relates to improvements in the devices used for the automatic lighting of aquatic torches or light buoys which are more particularly intended for seaplanes in order to facilitate alighting on water, signalling and other operations, and in which a composition is used which serves to produce an illuminating flame, which composition is the subject of French Patent No. 575,146 of December 29, 1923, as more definitely referred to hereinafter.

Hitherto, at the moment of using such apparatus, it was necessary first to tear off by hand the water-tight diaphragms in order to prepare for the operation of said apparatus. This operation, which is of the simplest nature *per se*, offers however a serious drawback, since in many cases and more particularly in aviation, the removal of the diaphragms by hand is sometimes difficult and dangerous owing to the time required for this operation, which is taken to the detriment of that of piloting, particularly if the pilot is alone and in danger.

Account must also be taken of occasional neglect to remove the diaphragms.

All these drawbacks and risks are now eliminated by the improvements made in this type of illuminating apparatus, the chief purpose of which is to eliminate any necessary previous operation and to effect their lighting automatically.

Said improvements are more particularly characterized by diaphragms formed of very thin water-tight materials and subjected to the movement of an actuating member which is itself subjected to the effects of the fall of the device for causing them to be torn off and perforated.

Said improvements are shown in the accompanying drawings which are given by way of a constructional example of one practical embodiment of the invention.

In said drawings:

Fig. 1 shows a longitudinal sectional view of the whole of the parts and elements forming an aquatic illuminating apparatus.

Fig. 2 shows a plan view partly taken in section along the line II—II of Fig. 3, of the arrangement of the partitions which hold in a normal position the composition serving to produce the illuminating flame.

Fig. 3 shows an elevation view of the apparatus illustrated in Fig. 1.

The aquatic apparatus or torch which is intended to have a sufficiently streamline shape with tail fins, comprises a cylindrical body 1 which terminates at each of its ends in the truncated conical portions 2 and 3. On the inside,

and in the upper part of the body 1, is located a water-tight chamber 4 which ensures the buoyancy of the apparatus in co-operation with ballast members 3a placed in the inverted cone 3.

The central part of the chamber 4 forms a cylindrical pipe 5 which opens at the upper end 6 of the apparatus.

In the lower part of the body 1 are arranged partitions 7 forming compartments, Figs. 1 and 10 2, which are intended to hold the illuminating composition in a normal position. Such a composition may, for example be a mixture of about 6 parts of calcium phosphide and about 1 part of calcium carbide, both of which constituents 15 tend to generate gases by decomposition upon contact with water. The calcium phosphide generates the gas hydrogen phosphide on contact with water and this gas ignites spontaneously upon contact with the air, while contact of calcium carbide with water generates acetylene gas which is promptly ignited by the automatic ignition of the hydrogen phosphide, giving an intense light capable of lasting for hours. Other proportions and even other compositions known 20 in the art may, of course be used, if desired, as the composition *per se* forms no actual part of the invention.

The central part of said compartments includes a perforated pipe 5a placed in the axial extension of the pipe 5. A cover 8, which is likewise perforated, closes said compartments.

It is to this known arrangement that the improvements apply which characterize the invention. Said improvements more particularly comprise a small cylinder 9 without a bottom and having a perforated wall, which cylinder is fixed on the lower end of the truncated conical portion 3. In said cylinder, at a predetermined height, is placed a diaphragm 10 which is preferably made of metal, and is slightly curved outwardly and is very thin, for example $\frac{1}{16}$ of a millimetre. The upper face of said diaphragm is in contact with a push member 11 secured to a rod or tube 12 which carries at its upper part 40 a perforated tube 13, the slightly conical end of which forms a valve 14 of which the stem is formed by an illuminating jet 15 fixed on this perforated tube 13.

At the required instant, the rod 12 can move 45 freely in the conduits 5 and 5a.

Towards the lower end of said rod 12, a diaphragm 16 is fixed to the rod by known means (welding), which diaphragm hermetically closes an orifice 17 of large diameter provided in the central part of a cap-shaped member 18, the lat-

ter being secured to the end 19 which closes the truncated conical portion 3 of the body 1, while on the other hand the illuminating jet 15, carried by the tube 13 and the rod 12, is adapted to bear upwardly on a diaphragm 20 that hermetically closes the upper orifice of the conduit 5 which opens at the top of the truncated conical portion 2. The jet 15 passes inside a bushing 21 which forms a seat for the valve 14.

A retracting spring 22 holds the valve 14 against the bushing 21.

Thus constructed, the improved apparatus operates in the following manner:

Due to the presence of its tail fins, the apparatus when released always falls in a vertical position in the water, and as soon as it touches the water, the diaphragm 10 is pushed back inside the cylinder 9 as would a piston, while moving, by means of the push member 11, the rod 12 in the direction of the arrow A. This movement, which is indicated in dotted lines, has the effect first of all of tearing away the diaphragm 16 and uncovering the orifice 17, and then of perforating the diaphragm 20 by means of the jet 15. At this instant, the tension of the spring 22 causes the contact of the tube 13 forming the valve 14 against the bush or seat of the valve 21 to occur.

As the diaphragm 16 has been torn away, the water penetrates inside the apparatus up to the water line B.

Due to the illuminating composition being moistened, illuminating gas is produced instantaneously and penetrates into the perforated tube 13 and into the jet 15 where it ignites on contact with the air in accordance with the principle described above and also set forth in the mentioned French patent.

An automatic operation is thus obtained which completely eliminates any necessary initial and sometimes difficult manipulation. These improvements make it possible to allow the apparatus to fall freely without any precaution and ensure completely automatic operation, by means of the appropriate shape of the apparatus, and by means of the special device described for the perforation of diaphragms which is obtained solely by the movement of a diaphragm which in turn only operates at the instant of the impact against the water or under a predetermined hydrostatic pressure. Said improvements constitute a most important advance in this kind of apparatus. In said apparatus the shapes, the dimensions and the materials used for its manufacture may vary without necessarily changing the general arrangement of the invention which has just been described.

Having now fully described my invention, I claim:

1. In an aquatic torch or light buoy of the character described, having a hollow elongated casing containing a combustible illuminating material and means for burning the same in a jet, means for directing and buoyantly maintaining said casing in an upright condition when in the water, the combination of a plurality of water-tight safety diaphragms individually sealing and protecting both the jet portion and said illuminating material from exposure, and operative means including a part of sufficient area to be effective upon contact with the water, to auto-

matically perforate and tear the water-tight safety diaphragms.

2. An aquatic torch or light buoy particularly adapted to be dropped from an airplane into water, comprising in combination, an elongated hollow casing having converging closed portions at the ends thereof, a transverse water-tight partition across the intermediate portion of the interior of said casing subdividing said interior into two main chambers, one of which serves to buoy up the device as a whole in the water and the other chamber to contain an illuminating gas producing composition, a substantially transverse foraminous partition subdividing said other chamber into a large end compartment forming the actual container for said gas producing material and a smaller chamber intermediate the two partitions, a conduit extending through said water-tight partition longitudinally through the casing and the first chamber therein to the converging end of said casing terminating said first chamber, gas burning means upon the outer end of said conduit, a foraminous conduit extending through said end compartment longitudinally of the casing from the foraminous partition through the converging end of the casing terminating said compartment, there being exterior means for maintaining said casing in vertical position when falling through the air, frangible diaphragms individually closing the outer end orifices of both of said conduits at the two ends of the casing, and operative means for automatically tearing and perforating said diaphragms upon contact of the buoy with water, said operative means being actuated by water pressure developed by impact of said buoy with the water.

3. An aquatic torch or light buoy according to claim 2, wherein the two conduits are substantially aligned and the diaphragm tearing and perforating means include a convex cap secured at the edges thereof to the outer end of the casing exteriorly of the end compartment, there being a central aperture in said cap, a foraminous hollow cylinder open at both ends secured at one of its ends to said outer end of the casing in a position to surround said cap, a convex hydrostatic diaphragm extending transversely across said foraminous cylinder and spaced exteriorly from said cap, a movable rod extending through the aperture in said cap and into both conduits, one of the frangible diaphragms secured to said rod and normally closing said aperture in the cap, a head upon the end of said rod disposed exteriorly of said cap and contacting with said hydrostatic diaphragm, a foraminous tube upon the other end of said rod having a converging portion terminating in and carrying a jet forming gas burning means adjacent the end of the casing terminating the water-tight chamber, a valve seat disposed within the outer end of the conduit terminating at said latter end of the casing and cooperating with the converging end of said rod, the other frangible diaphragm normally closing said outer end of said latter conduit and the gas jet being adapted to slide in said outer end of the conduit during movement of said rod, and resilient means tending to urge the rod toward said valve seat in order to press said converging end of said rod into contact with said seat.

ANTOINE THIEBAULT.
